ADJUSTABLE SOLE GAUGE FOR RIB APPLYING MACHINE

Einar H. Hanson, Lynn, and Kenneth G. Strom, Saugus, Mass., assignors to Prime Manufacturing Company, Lynn, Mass., a corporation of Massachusetts

Application February 8, 1957, Serial No. 639,019

4 Claims. (Cl. 12—20)

This invention comprises a new and improved edge gauge mechanism for rib applying machines operating to apply a sewing rib to a flat insole blank preparatory to the manufacture of welt shoes.

In preparing welt insoles it is desirable to space the sewing rib a substantial distance within the margin of the insole throughout its shank portions, to locate the rib more closely adjacent to the margin of the insole throughout the ball portion on both sides thereof, and to locate the rib about the toe portion of the shoe with an intermediate spacing, that is to say, intermediate between the spacing of the rib in the shank and in the ball portions of the insole. The edge gauge of the present invention is designed to enable the operator conveniently and accurately to make these three required settings of the edge gauge in the required order as the insole is automatically fed through the machine at a high rate of speed.

The improved gauge mechanism is herein shown in a machine so constructed and arranged that the sole supporting element together with the edge gauge is movable from operative to inoperative position at the conclusion of each rib applying operation in order to permit the insertion of fresh work to the machine. A feature of the invention resides in an adjustable edge gauge so organized as to take part in such movement of the sole support while preserving its integrity against disburiance or misplacement.

Another feature of the invention comprises adjustable stops for determining the range of movement of the gauge in combination with means for adjustably determining an intermediate position.

These and other features of the invention will be best understood and appreciated from the following description of a preferred embodiment thereof selected for purposes of illustration and shown in the accompanying drawings in which:

Fig. 1 is a plan view showing the sole-supporting and gauging mechanism with a portion of an insole in operative position,

Fig. 2 is a plan view of a ribbed insole illustrating the desired spacing of the sewing rib,

Fig. 3 is a view in elevation, partly in section, on the line 3—3 of Fig. 1,

Fig. 4 is an end view of the sole-supporting roll and adjustable parts, and

Fig. 5 is a cross-sectional view on the line 5—5 of Fig. 1.

For purposes of illustration the gauge mechanism of the present invention is shown as embodied in a rib applying machine of the type shown in U.S. Patent No. 2,142,332, Ridderstrom, to which reference may be had for further details of the machine which are not illustrated herein. As in the machine of that patent the sole-supporting and gauging mechanisms are carried by an arm 10 pivotally mounted in the frame of the machine for downward movement from operative to inoperative posi-

2

tion with respect to the sole feeding and strip guiding elements of the machine which are mounted at a fixed level. The arm 10 is held temporarily at its lower inoperative position by a pair of toggle links, the lower of which is partially shown in Figs. 1 and 3. When this toggle is broken, the arm 10 and all the parts carried thereby are lifted to operative position.

The work support comprises a roll 12 mounted to rotate freely about a horizontal axis and cooperating with the roll is a pair of feed feet 13, shown in Fig. 4, which are operated as shown in the patent above identified to engage the rib stripping as it is directed to the insole 16 and advance the insole and rib to the left as shown in Fig. 4. A portion of the rib stripping guide 14 is shown in Fig. 1 and this, as already noted, is maintained at a fixed level in the organization of the machine. The stripping 15 is shown in Figs. 1 and 4 as it is directed to the upper face of an insole 16.

Fig. 2 shows a welt insole 16 as produced by the mechanism of the invention with an upright sewing rib 15' correctly located thereon. In practice the operator starts at approximately the breast line on the inside shank portion of the insole with the gauge set to space the rib inwardly from the edge of the sole. As the ball is reached the location of the rib is shifted outwardly so that the outer flange of the rib coincides with the edge of the sole. This spacing is continued until the toe is reached whereupon the gauge is shifted to locate the rib again inwardly from the edge of the insole but with less spacing than that employed in the shank. After rounding the toe the gauge is shifted outwardly in passing about the ball of the sole, and finally the gauge is shifted inwardly for the relatively wide spacing required in the outside shank. The gauge mechanism for effecting these desired shifts will now be described.

A block or base member 17 is fixedly connected to the arm 10 and has an upstanding land or platform portion 18 in which is journaled an upright pivot shaft 20. To the lower end of this shaft is pinned the forward portion 19 of a hand lever 21 arranged to swing about the axis of the shaft 20 beneath the base member 17 and in so doing to rock the shaft 20. The outer edge of the base member 17 is curved on a radius from the axis of the pivot shaft 20 and provided with an intermediate detent 22 with which cooperates a spring retracted dog or bolt 23 arranged to be advanced by the operator into engagement with the detent 22 by a trigger 24 pivotally mounted on the hand lever 21. In Figs. 1 and 3 the trigger is shown as rocked by the operator so that the bolt 23 is advanced against spring pressure into a position to engage the detent 22 when the hand lever is rocked in counter-clockwise direction as shown in Fig. 1.

The bolt 23 is mounted in a block 25 adjustably supported between arms 26 and 27 fast to the hand lever. The block 25 is carried by an adjusting screw which passes through the arms 26 and 27 and is provided with an operating knob 28 at one end and with lock nuts 29 at the other. It will be seen that by turning the adjusting screw 28 the relative position of the bolt 23 and the hand lever may be adjusted and the intermediate position of the lever thus regulated. A short key-way is provided in the upper surface of the bolt 23 for the reception of a screw 30 which is threaded into the block 25 and serves to hold the bolt 23 against twisting.

The edge gauge 31 itself is formed as a part of a plate screwed to an underlying plate 32 as shown in Figs. 1 and 5. The plate 32, in turn, is secured to the outer end of a transverse shaft 33. An inner shaft 34 is telescopically and adjustably received in the shaft 33 and provided at its inner end with an enlarged head to which is secured a plate 35. To the plate 35 is secured a

block 36 carrying an angle piece 37 and forming therewith a yoke opening toward the left as shown in Fig. 1. A ball end crank arm 38 is received between the sides of the yoke 36, 37 and this projects outwardly from an enlarged head 20, formed as a part of the pivot shaft 20. It will be seen that oscillation of the hand lever is effective to rock the crank arm 38 shifting the yoke 36, 37 in one direction or the other and correspondingly moving the edge gauge 31 through its telescopic shaft connections.

An abutment screw 39 projects downwardly from the bottom of the base member 17 and this is arranged to be engaged by one or the other of adjusting screws 40 and 41 threaded into opposite sides of the hand lever 19, 21. These screws by engaging the abutment adjustably limit the oscillation of the hand lever and define its range of movement.

In practice the operator will start the machine with the hand lever positioned by the adjusting screw 41 as indicated by the "Start and Finish" position indicated in Fig. 1 with the edge gauge 31 in its position of maximum advance to control the wide inside shank spacing of the rib as applied to the insole. In reaching the ball of the sole the operator will swing the hand lever in a clockwise direction until arrested by the adjusting screw 40 with the gauge in its position of minimum advance corresponding to the outward position of the rib. When the toe of the sole is reached the operator will swing the hand lever in a counter-clockwise direction until the bolt 23 engages the detent 22, holding the edge gauge 31 in an intermediate position corresponding to the desired spacing of the rib about the toe portion of the insole. After the toe has been passed the operator will swing the hand lever back again to the adjusting screw 40 and for the outside shank spacing the trigger 24 will be released and the bolt 23 retracted so that the hand lever may be moved without interruption back to starting position determined by the adjusting screw 41. It will also be apparent that the single adjustment of the lever 21 by the adjusting screw 28 results in a corresponding adjustment of the edge gauge 31 in all three of its operating positions.

Having thus disclosed our invention and described in detail a preferred embodiment thereof, we claim as new and desire to secure by Letters Patent:

1. In a rib applying machine, gauge mechanism comprising a base member supported for bodily movement to and from operative position, an upright pivot shaft journaled in the base member, a hand lever pivotally connected to the shaft below the base member, an abutment projecting below the base member, stop screws carried by the hand lever and arranged to contact the abutment adjustably to limit the movement of the hand lever in opposite directions, and a sole gauge connected to and operated by rotary movement imparted to said pivot shaft by the hand lever.
2. Gauge mechanism as defined in claim 1 further characterized by a detent on the base member and an adjustable stop on the hand lever for determining an intermediate position of the hand lever within its range of movement.
3. Gauge mechanism as defined in claim 1 further characterized by a crank arm carried by the upright pivot shaft and a cooperating yoke forming a part of the connection to the sole gauge.
4. Gauge mechanism for a rib applying machine comprising a base member having an upright pivot shaft extending above and below it, a hand lever fast to the lower end of the pivot shaft and a crank arm fast to its upper end, an abutment projecting from the base member, opposed adjusting screws mounted on the hand lever in position to engage opposite sides of the abutment and so define its range of oscillation about the axis of said pivot shaft, releasable means for arresting the hand lever in an intermediate position within its range of movement, a sole gauge, and operating connection therefor operated by the crank arm of the pivot shaft.
